UNITED STATES PATENT OFFICE

2,298,804

EXPANSION VALVE

Alwin B. Newton, Minneapolis, Minn., assignor to
 Minneapolis-Honeywell Regulator Company,
 Minneapolis, Minn., a corporation of Delaware

Application September 26, 1938, Serial No. 231,684

17 Claims. (Cl. 62—127)

This invention relates to expansion valves for use in refrigeration systems and more particularly to expansion valves of the automatic type controlled by superheat at the evaporator outlet.

This application is a continuation in part of my co-pending application, Serial No. 192,818, filed February 26, 1938.

Thermostatic expansion valves may be divided into two general classifications, namely, those whose operating elements are in the form of bellows and those employing diaphragms as the operating elements. In the bellows type of expansion valve, difficulty has been experienced in the past due to the fact the bellows is exposed to refrigerant on one side and to humid atmospheres on the other side, thus causing rapid deterioration of the bellows, whereas if the bellows are maintained entirely out of contact with the atmosphere, the main cause of deterioration of the bellows is removed. This I have been able to accomplish by a novel arrangement of the bellows, thereby retaining the known advantages of the bellows type of thermostatic expansion valve while eliminating the disadvantage thereof. One of the objects of my invention is therefore the provision of a thermostatic expansion valve of the bellows actuated type wherein the bellows are exposed on both sides to refrigerant thereby reducing the danger of rupture of the bellows.

Another object of my invention is the arrangement of the bellows so that in case any one of the bellows should rupture, no refrigerant would be lost therethrough.

A further object of my invention is the provision of means to eliminate hunting of the valve.

Another object is the provision of a power unit for an expansion valve which may readily be applied directly to the expansion valve or to a pilot valve for causing the operation of a large size expansion valve.

Another object of the invention is the provision of a sealing bellows in addition to the operating bellows for the valve for further reducing the danger of leakage of the refrigerant, together with means for compensating for the spring rate of the bellows.

A further object of my invention is the novel arrangement of a thermostatic expansion valve operated in accordance with the superheat at the evaporator outlet wherein no sealed operating bulb is employed.

A further object of the invention is the provision of a novel bellows arrangement for operating a thermostatic expansion valve so as to maintain

a substantially constant degree of superheat for varying pressures at the evaporator outlet.

A further object of the invention is the provision of an expansion valve which may be interchangeably used with refrigeration systems using different kinds of refrigerants.

Another object is the provision of means for connecting the valve operating means to the interior of the evaporator outlet at a single point.

Other objects will become apparent upon a study of the specification, claims, and appended drawing, in which like reference characters represent like parts in the various views and in which:

Figure 1 is a view showing a refrigeration system in which an expansion valve embodying a preferred form of my invention is illustrated partly in cross section;

Figure 2 is a section taken along the line 2—2 of Figure 1; and

Figure 3 is a view along the line 3—3 of Figure 1.

Referring more particularly to the drawing, a conventional form of refrigeration system is illustrated, this system including a compressor 10 for compressing a refrigerant and forcing it through pipe 11 to a condenser 12 wherein the refrigerant is condensed and flows to a receiver 13 from which it flows through a pipe 14 through expansion valve 15 where the refrigerant is expanded, the expanded refrigerant thus flowing through pipe 16 to an evaporator 17 where the refrigerant absorbs heat from the surrounding atmosphere and evaporates and then flows through pipe 18 back to the compressor 10. The compressor 10 may be controlled in any conventional manner.

The expansion valve 15 includes a valve casing 20 and a chamber 21 housing the operating mechanism. Valve casing 20 includes an inlet 22 to which is suitably connected in any suitable manner the pipe 14, and an outlet 24 to which is suitably connected the pipe 16. Refrigerant flows through the inlet 22 through a passageway 23 into a chamber 25. A valve element 26 cooperating with a removable valve seat 27 controls the flow of refrigerant from the chamber 25 into a passageway 28 which leads to the outlet 24. The valve element 26 is carried by a lever 30 pivoted at 31 in a recess formed in the outer wall of the valve casing 20. A spring 32 bears against the downwardly extending arm 33 of the lever 30, this spring being seated in a suitable recess formed in the outer wall of the valve chamber 20. Valve casing 20 and the casing 21 may be connected together in any suitable manner and flanges 34 and 35 may be proved on the outer walls of the

casings 20 and 21 and suitably secured together by bolts 36. Pins 37 may be provided for properly aligning the two casings together and a sealing gasket 38 of any suitable material may be interposed between the casings. Casing 20 may be open on that portion which is contiguous the casing 21, there being a suitable opening 39 formed in the wall of the casing 21 which separates the two chambers from one another. Lever 30 may be in the form of a yoke as illustrated in dotted lines in Figure 3 and includes arms 40 which extend through the opening 39 into the casing 21, these arms 40 being biased upwardly by means of spring 32 into engagement with pins 41. These pins 41 are carried and moved by the operating mechanism in casing 21 as will be clearly described later.

The casing 21 houses a pair of bellows 45 and 46 which are axially aligned and are connected together and separated from one another by a cup-shaped member 47. The bellows 45 may be secured between a member 49 and the upper wall of the casing 21, member 49 being secured to the upper wall of the casing 21 in any suitable manner. A cup-shaped member 48 is provided in the lower wall of the casing 21 and the bellows 46 may be secured between this member and the lower wall portion of the casing 21. The member 47 forms a wall which separates the bellows 45 and 46 into a pair of separated chambers and in the upper portion of the member 47 is suitably fitted a nipple 50 having a restricted opening therethrough and providing communication between the interior of the bellows 45 and the chamber formed between the outside of the bellows 45 and 46 and the casing 21. It will be noted that this chamber formed between the bellows and the casing 21 is in communication by means of the opening 39 in the interior wall of casing 21 with the valve chamber 25 so that the valve chamber 25 and the chamber surrounding the bellows 45 and 46 are at all times during the operation of the system filled with warm refrigerant entering valve chamber 25 through inlet 22.

Connected to the bottom portion of member 47 is a vertically extending rod 52 which extends through an opening in the bottom portion of member 49, a bellows 56 being suitably secured to this rod at a point remote from the bottom thereof and the lower portion of this bellows being suitably secured to the lower wall portion of member 49. To the upper portion of rod 52 is threaded a nut 58 against the under side of which bears a compression spring 59. The lower portion of spring 59 bears against the lower portion of a yoke 60, as more clearly illustrated in Figure 2, the upper portion of this yoke being connected to a rack 61 with which engages a gear 62 connected to a motor 63 for a purpose to be later described. At any given time the yoke 60 will be held in a fixed position and the spring 59 bearing against the bottom of the yoke and the nut 58 biases the rod 52 and accordingly the member 47 connected thereto in an upwardly direction.

Secured to the cup-shaped member 48 in the bottom of casing 21 is a fitting 65 having an inlet 66 communicating with a passageway 67 which communicates with the interior of the bellows 46. A pipe 68 is suitably secured within the inlet 66 of fitting 65, the other end of this pipe being secured by a suitable fitting 69 to the outlet of the evaporator 17. This fitting 69 may include a nipple 70 threaded at one end into the outlet of the evaporator and a nut 71 threaded

onto the other end of the nipple and securing the end of pipe 68, which may be flared, between the nut and outer portion of the nipple. Extending through the pipe 68 and spaced from the walls thereof is a small tube 74 which is suitably secured to the fitting 65 and communicates with a passageway 75 extending upwardly through the fitting 65. To the outlet portion of passageway 75 is secured a small tube 76 which may be spirally arranged within the bellows 46 and of flexible material. The upper end of this tube extends through a wall of the wall member 47 separating the bellows 45 and 46 from one another. Pipe 74 extends through the nipple 10 and into the outlet of the evaporator 17, this pipe terminating in a nozzle 78, which nozzle is directed away from the evaporator 17.

The bellows 46 is in communication by means of the pipe 68 with the outlet of the evaporator 17 and is accordingly subject to variations in the pressure of the refrigerant at the outlet of the evaporator. The upper bellows 45 is in communication by means of nipple 50 with the chamber formed between the bellows 45 and 46 and the casing 21 so that the warm refrigerant surrounding these bellows is able to pass through the small passageway in the nipple 50 where it is expanded into the bellows 45. This bellows is also in communication by means of the tube 76, the tube 74 and nozzle 78 with the outlet of the evaporator so that the pressure existing within the bellows 45 may be considerably less than the pressure of the refrigerant surrounding the bellows, this latter refrigerant being on the high pressure side of the refrigeration system. There will accordingly be a considerable pressure differential between the exterior and the interior of bellows 45. It is well known that a gas passing through a small nozzle has a critical pressure. In other words, when the pressure differential through the nozzle has reached a certain value, the nozzle will pass a maximum amount of gas which amount will not be increased as the pressure drops. With common refrigerants the critical pressure value will be somewhere in the neighborhood of .97 as the liquid refrigerant expands into a gas. In other words, if the pressure on the low pressure side of the nozzle is less than 97% of the pressure on the high pressure side of the nozzle the same amount of refrigerant will pass therethrough, for a given head pressure, as will pass if the pressure on the low pressure side of the nozzle is further decreased. Therefore the amount of refrigerant flowing through the nipple 50 will not vary appreciably during the operation of the system since the pressure within the bellows 45 will always be less than 97% of the pressure on the outside of the bellows so that there will be a constant flow from the chamber surrounding the bellows 45 and 46 of the refrigerant through the nipple 50 and into the interior of bellows 45.

The refrigerant, upon passing through the nipple 50 expands and enters the chamber 45 and becomes evaporated thus filling the chamber 45, tube 76, and tube 74 with evaporated refrigerant. It should be noted at this point that the bellows 45 is surrounded by warm liquid refrigerant from the condenser 13 so that the refrigerant within the bellows will remain in the evaporated condition. The refrigerant passes outwardly through pipe 74 to the nozzle 78. This nozzle is also of small size so that the refrigerant will leave the pipe 74 through this nozzle at a slow rate. Because of the flow characteristics of the nozzle

78, when the refrigerant is in liquid form, a greater weight of refrigerant will flow therethrough per unit time than when the refrigerant is in gaseous form so that the amount of refrigerant in bellows 45 will depend upon the state of the refrigerant at the nozzle 78, which in turn depends upon the temperature at the evaporator outlet. The refrigerant at the end of the pipe 14 and the nozzle 78 is subjected to the temperature of the refrigerant leaving the evaporator 17 and since this temperature is low, it will condense the refrigerant in the nozzle 78 so that the refrigerant will flow through the nozzle 78 at a greater weight rate than if the refrigerant were in gaseous form. The nozzle 78 and the 15 end of the pipe 14 accordingly form a condensing surface. The orifice of the nozzle 78 will act to maintain a small liquid surface at the entrance thereof, and the temperature of this liquid refrigerant determines the pressure in the bellows 45, and accordingly this bellows responds to the pressure corresponding to the temperature of the refrigerant in the outlet of the evaporator. The pressure acting downwardly against the plate member 47 will accordingly depend upon the temperature of the refrigerant at the evaporator outlet and since the bellows 46 is subjected to the suction pressure at the evaporator outlet it will be seen that the plate 47 moves in accordance with actual pressure at the evaporator outlet and in accordance with the pressure corresponding to the temperature of the refrigerant leaving the evaporator, or in other words, in accordance with variations in superheat of the refrigerant in the evaporator outlet.

The movement of pins 41 downwardly causes the opening of valve 26, this downward movement of the pins occurring when the pressure acting downwardly on the plate 47, which pressure is the pressure corresponding to the temperature of the refrigerant is greater than the suction pressure at the evaporator outlet plus the pressure exerted by spring 59 or in other words, when the superheat at the outlet of the evaporator reaches a predetermined value. The opening of the valve 26 permits an increased flow of refrigerant through pipe 16 and evaporator 17 whereupon the pressure at the evaporator outlet increases and/or the temperature decreases and the valve is again permitted to move towards 50 closed position.

The provision of bellows 56 which forms a sealing bellows between the rod 52 and the upper portion of bellows 45 reduces the effective area of the bellows 45 since the pressure within this bellows exerts an upward force on the bellows 56 tending to move the rod 52 upwardly so that the effective area of bellows 45 is less than that of bellows 46 by an amount corresponding to the area of the bellows 56. By reason of this, when spring 59 is properly adjusted it is possible to maintain a constant superheat at the evaporator outlet so that a uniform portion of evaporator 17 will be available for cooling purposes regardless of the temperature and pressure existing at the outlet thereof. This would not be true were the effective area of the two bellows equal since the relation between pressure and temperature for known refrigerants is not a straight line relationship so that the pressure exerted by the bellows 45 which will be termed the power bellows does not vary directly with the temperature. In other words, as the temperature of the refrigerant increases the pressure corresponding to the temperature increases at a 75

greater rate. For this reason, the amount of superheat in the return line where the effective areas of the bellows are equal, varies with varying temperatures therein, the lower the temperature the greater amount of superheat since the degree of superheat depends upon the difference in the temperature in the return line and the temperature corresponding to the pressure in the return line or evaporator outlet. This effect is 10 effectively compensated for by making the effective area of the power bellows somewhat smaller than the effective area of the bellows which is subjected to the outlet pressure.

The provision of the nipple 50 and the nozzle 15 78 eliminates the necessity of using the customary temperature bulb having a sealed fill while producing the same results as has heretofore been obtained with the sealed fill. It is also possible to make a single connection to the suction line for the power bellows and the pressure bellows even where the outlet line is of small size which might not be possible with the conventional construction utilizing the bulb with the sealed fill. By reason of this single connection it is assured that the bellows will accurately correspond to the superheat at a single point in the outlet of the evaporator and by having the nozzle located within the suction line it is possible to obtain quicker response of the valve to variations in superheat. Also, since no sealed operating fill is required, the expansion valve may be interchangeably used with refrigeration systems using different kinds of refrigerants without affecting the superheat maintained at the evaporator outlet by properly adjusting the valve.

To prevent hunting of the valve, I have provided a suitable friction damping means for preventing the operation of the valve in response to minute changes in superheat at the evaporator outlet. A friction plate 80 is fixedly secured to the upper wall of the casing 21, this plate bearing against one side of the rod 52. A second plate 81 of any suitable friction material is slidably supported on the top of the casing 21 diametrically opposite from the plate 80, this plate being slotted as at 82 and being slidably held in place by means of a bolt 83. A spring 84 is secured as at 85 to the side of casing 21 and bears against the end of the plate 81. The force exerted by this spring on the plate 81 may be varied by means of a bolt 86 threaded into the side of the casing 21. Thus a force resisting the movement of the rod 52 and therefore of the valve 26 is provided by the plate 81, this force being adjustable by means of the bolt 86 so that it will require more than just a minute change in the degree of superheat at the evaporator outlet to cause any movement of the valve 26, whereby the danger of the valve hunting in response to minute changes in superheat may be effectively prevented.

The sealing bellows 56, as well as the bellows 45 and 46 and the tube 76 will have a spring rate that may be suitably compensated for. This compensating means may include a circular spring 90 suitably secured as at 91 to the upper portion of the member 49, this spring having a single turn with the ends thereof spaced apart as illustrated. Suitable toggle links 93 and 94 are notched at their outer ends and fit over the reduced inner portion of spring 90, the inner ends of these links being reduced and fitting within notches 95 formed in the upper portion of rod 52. Upon a downward valve opening movement of the plate member 47, the bellows 46 and 56 and tube 76

tend to become compressed and this compression of the bellows and tube will tend to oppose the downward movement of the plate 47. Similarly, the expansion of bellows 45 tends to cause the downward movement of plate 47. However as member 52 moves downwardly, the inner portions of toggle links 93 and 94 will also be moved downwardly and by reason of the force exerted by spring 90 these links will exert a downward force on the rod 52 which force increases as the plate 47 moves downwardly and the bellows and tube become more compressed. This action of the toggle links in tending to urge the rod 52 downwardly may be arranged to just compensate for the spring rate of the various parts so that these parts will have no effect whatever on the movement of the plate 47 and therefore will not tend to oppose the opening of the expansion valve.

Any suitable condition responsive device such as a thermostat 100 may be mounted in the space being cooled, this thermostat comprising a bimetallic element 101 and an arm 102 connected to the bimetallic element 101 and movable thereby in response to changes in temperature in the space being cooled. Arm 102 is arranged to sweep across a resistance 103 in response to temperature changes in the space being cooled, this resistance being connected at its ends by means of conductors 104 and 105 to terminals 106 and 107 of the motor 63. The bimetallic element 101 is connected by means of conductor 108 to motor terminal 109. Power may be supplied to the motor by means of conductors 110 and 111 connected to a suitable source of power, not shown. Motor 63 is of the proportioning type and may be constructed in the manner shown by the patent to D. G. Taylor No. 2,028,110 issued January 14, 1936. This motor is a reversible motor, the direction of rotation and the extent of rotation being dependent upon the position of arm 102 with respect to resistance 103 as is clearly set forth in that patent. As the temperature in the space being cooled rises, the arm 102 moves to the right across the resistance 103 and causes rotation of motor 63 an amount proportional to the extent of movement of the arm 102 in a direction to cause a decrease in the tension of spring 59 so that the amount of superheat required to open the valve 26 is decreased. In other words, the pressure corresponding to the temperature of the refrigerant at the evaporator outlet which is required to overcome the force exerted by the suction pressure within the bellows 46 and the spring 59 is decreased due to the decrease in the force exerted by the spring 59, and by decreasing the amount of superheat at the evaporator outlet, a greater portion thereof is available for cooling purposes. Conversely if the temperature in the space should drop indicating the need for less cooling within the evaporator, arm 102 of thermostat 100 moves to the left over resistance 103, causing the motor to rotate in a direction to increase the force of the spring 59 so that a greater amount of superheat is required to open the valve and a smaller portion of the evaporator will be filled with liquid refrigerant and accordingly will be available for cooling purposes. The downward movement of the yoke member 60 may be limited by means of the friction damping means consisting of the members 80 and 81.

It will be noted that with the bellows 45 and 46 arranged in the manner illustrated, that both sides thereof are at all times exposed to refrigerant and at no time is any portion of the bellows exposed to the atmosphere so that the

life of the bellows is materially increased and the main cause of rupture thereof is eliminated. The superheat that will be maintained at the evaporator outlet for any given temperature in the space being cooled may be varied by adjusting the position of nut 58 on the rod 52 so as to vary the tension of the spring 59 and accordingly vary the force required to open the valve for any given temperature.

It will now be understood that the valve 26 may be moved in a manner to maintain a constant degree of superheat at the evaporator outlet, as long as the spring 59 is properly adjusted. As the cooling load on the system varies, the spring 59 will be adjusted by the motor 63 so as to vary the superheat maintained at the outlet of the evaporator and the effective cooling surface of the evaporator. By means of my unique arrangement wherein the necessity of using a sealed fill with the expansion valve is eliminated, the valve may be readily applied to any refrigeration system regardless of the kind of refrigerant used therein. The use of the friction damping means effectively prevents hunting of the system due to minute variations in superheat at the evaporator outlet, whereas accurate response of the valve due to larger variations in superheat at the evaporator outlet is assured by reason of the means for compensating for the spring rate of the various parts of the valve, and by reason of the arrangement of the bellows.

Having described a preferred form of my invention, many modifications may become apparent to those skilled in the art, and it should be understood that my invention is limited only by the scope of the appended claims.

I claim as my invention:

1. In a refrigerating system having a condenser, an evaporator and an expansion valve for controlling the flow of refrigerant from the condenser to the evaporator, the combination of means for by-passing a small amount of refrigerant from the high pressure side of the expansion valve to the evaporator outlet, said means being arranged to cause condensation of said by-passed refrigerant, and means for controlling the position of the expansion valve in response to the rate of condensation of the by-passed refrigerant.

2. In a refrigerating system having a condenser, an evaporator and an expansion valve for controlling the flow of refrigerant from the condenser to the evaporator, operating means for positioning said expansion valve in a manner to maintain a substantially constant degree of superheat at the outlet of the evaporator, said operating means including a member movable in response to pressure variations on opposite sides thereof, means subjecting one side of said member to the pressure of the refrigerant on the low pressure side of the refrigerating system, means for conducting refrigerant to the opposite side of said member at a substantially constant rate, and means for conducting refrigerant from said opposite side at a rate that depends upon the temperature of the refrigerant at the evaporator outlet whereby said other side of said member is subjected to a pressure that varies as the pressure corresponding to the temperature of the refrigerant at the evaporator outlet varies.

3. In a refrigerating system having a condenser, an evaporator and an expansion valve for controlling the flow of refrigerant from the condenser to the evaporator, the combination of,

pressure responsive actuating means for said expansion valve, means providing communication between one side of said actuating means and the low pressure side of the refrigerating system, conduit means providing communication between the high pressure side of the refrigerating system, the other side of said actuating means and the low pressure side of the refrigerating system, the communication between the high pressure side of the system and said other side of the actuating means being of small size, a portion of said conduit means being located in the evaporator outlet to cause condensation of refrigerant in said portion, whereby the temperature of the refrigerant at the evaporator outlet 15 determines the pressure on said other side of the actuating means.

4. In a refrigerating system having a condenser, an evaporator and an expansion valve for controlling the flow of refrigerant from the condenser to the evaporator, the combination of, pressure responsive actuating means for said expansion valve, means providing communication between one side of said actuating means and the low pressure side of the refrigerating system, means conducting refrigerant from the high pressure side of the refrigerating system to the other side of the actuating means at a substantially constant rate, conduit means conducting refrigerant from said other side of the actuating means to the low pressure side of the refrigerating system, and a portion of said conduit means located in the evaporator outlet to cause condensation of refrigerant in said portion, whereby the temperature of the refrigerant at the evaporator outlet determines the pressure on said other side of the actuating means.

5. In a refrigerating system having a condenser, an evaporator and an expansion valve for controlling the flow of refrigerant from the condenser to the evaporator, the combination of, pressure responsive actuating means for said expansion valve, means providing communication between one side of said actuating means and the low pressure side of the refrigerating system, a small leak port between the high pressure side of the refrigerating system and the other side of the actuating means, a tube providing communication between said other side of the actuating means and the interior of the evaporator outlet and having a small port at the end within the evaporator outlet, the temperature of condensation of refrigerant leaving said tube being determined by the temperature at the evaporator outlet and determining the pressure on said other side of the actuating means, said leak port being of such a size that the flow of refrigerant therethrough remains substantially constant during the operation of the refrigerating system regardless of the temperature of condensation within said tube, whereby the pressure on said other side of the actuating means is proportional to the temperature of the refrigerant at the evaporator outlet.

6. In a refrigerating system having a condenser, an evaporator and an expansion valve for controlling the flow of refrigerant from the condenser to the evaporator, the combination of, a pair of opposed extensible chambers, one end of each of said chambers being rigidly connected together and said ends having rigid imperforate wall portions forming pressure areas, means operatively connecting the expansion valve with the connection between said chambers for operation thereby, means connecting one chamber to 75

the low pressure side of the refrigerating system, means conducting refrigerant from the high pressure side of the refrigerating system to the other chamber at a substantially constant rate, 5 means conducting refrigerant from said other chamber to the low pressure side of the refrigerating system at a rate that varies in proportion to the variations in the pressure corresponding to the temperature of the refrigerant at the outlet of the evaporator, and a bellows within said last named chamber for decreasing the effective pressure area of the wall portion thereof and being of such a size as to insure the maintenance of a substantially constant degree of superheat at the evaporator outlet for varying degrees of pressure and temperature at said outlet.

7. In a refrigerating system having a condenser, an evaporator and an expansion valve for controlling the flow of refrigerant from the condenser to the evaporator, the combination of, a pair of opposed extensible chambers, one end of each of said chambers being rigidly connected together and said ends having rigid imperforate 20 wall portions forming pressure areas, means operatively connecting the expansion valve with the connection between said chambers for operation thereby, means connecting one chamber to the low pressure side of the refrigerating system, 25 means conducting refrigerant from the high pressure side of the refrigerating system to the other chamber at a substantially constant rate, means conducting refrigerant from said other chamber to the low pressure side of the refrigerating system at a rate that varies in proportion 30 to the variations in the pressure corresponding to the temperature of the refrigerant at the outlet of the evaporator, a bellows within said last named chamber for decreasing the effective pressure area of the wall portion thereof and being of such a size as to insure the maintenance of a substantially constant degree of superheat at the evaporator outlet for varying degrees of pressure and temperature at said outlet, and means 35 for counteracting the effects of the variations in force exerted by the extensible chambers upon expansion and contraction thereof.

8. In a refrigerating system having a condenser, an evaporator and an expansion valve for 40 controlling the flow of refrigerant from the condenser to the evaporator, the combination of, a pair of opposed extensible chambers, one end of each of said chambers being rigidly connected together and said ends having rigid imperforate 45 wall portions forming pressure areas, means operatively connecting the expansion valve with the connection between said chambers for operation thereby, means connecting one chamber to the low pressure side of the refrigerating system, 50 means conducting refrigerant from the high pressure side of the refrigerating system to the other chamber at a substantially constant rate, means conducting refrigerant from said other chamber to the low pressure side of the refrigerating system at a rate that varies in proportion 55 to the variations in the pressure corresponding to the temperature of the refrigerant at the outlet of the evaporator, a bellows within said last named chamber for decreasing the effective pressure area of the wall portion thereof and being of such a size as to insure the maintenance of a substantially constant degree of superheat at the evaporator outlet for varying degrees of pressure and temperature at said outlet, and damping 60

means for preventing hunting of the expansion valve.

9. In a refrigerating system having a condenser, an evaporator and an expansion valve for controlling the flow of refrigerant from the condenser to the evaporator, the combination of, means for by-passing a small amount of refrigerant from the high pressure side of the expansion valve to the evaporator outlet, means forming part of said by-passing means for causing condensation of said by-passed refrigerant in the evaporator outlet, means for controlling the position of the expansion valve in response to the temperature of condensation of the by-passed refrigerant, and means for varying the force required to open the expansion valve whereby the degree of superheat maintained at the evaporator outlet is varied.

10. In a refrigerating system having a condenser, an evaporator and an expansion valve for controlling the flow of refrigerant from the condenser to the evaporator, operating means for positioning said expansion valve in a manner to maintain a substantially constant degree of superheat at the outlet of the evaporator, said operating means including a member movable in response to pressure variations on opposite sides thereof, means subjecting one side of said member to the pressure of the refrigerant on the low pressure side of the refrigerating system, means for conducting refrigerant to the opposite side of said member at a substantially constant rate, means for conducting refrigerant from said opposite side at a rate that depends upon the temperature of the refrigerant at the evaporator outlet whereby said other side of said member is subjected to a pressure that varies as the pressure corresponding to the temperature of the refrigerant at the evaporator outlet varies, and means for rendering the effective pressure area of said other side of the member less than the effective pressure area of said one side.

11. In a refrigerating system having a condenser, an evaporator and an expansion valve for controlling the flow of refrigerant from the condenser to the evaporator, the combination of, means responsive to the condition of the refrigerant on the low pressure side of the refrigerating system for controlling the operation of the expansion valve, said means including resilient means that become stressed upon operation of the expansion valve to various positions, and means for counteracting the effects of the variations in force exerted by the resilient means so that stresses set up therein will not affect materially the position of the expansion valve.

12. In a refrigerating system having a condenser, an evaporator and an expansion valve for controlling the flow of refrigerant from the condenser to the evaporator, the combination of, extensible means controlling the position of the expansion valve, means causing the extensible means to respond to the superheat at the outlet of the evaporator whereby said expansion valve is positioned in accordance with the superheat at the evaporator outlet, and means for counteracting the effects of the variations in force exerted by the extensible means so that stresses set up therein will not affect materially the position of the expansion valve.

13. In a refrigerating system having a condenser, an evaporator and an expansion valve for controlling the flow of refrigerant from the condenser to the evaporator, the combination of, a first bellows, a second bellows in axial alignment

with said first bellows, wall means separating said bellows and movable therewith, a rod connected to said wall means and extending axially through the interior of the first bellows, spring means cooperating with the rod to urge said wall means in one direction, means for sealing the interior of the second bellows and for subjecting the interior thereof to the pressure of the low pressure side of the refrigerating system, a sealing bellows connected to the rod for sealing the interior of the first bellows, means for subjecting the interior of the first bellows to a pressure corresponding to the temperature of the refrigerant in the outlet of the evaporator, means operated by the wall means for operating the expansion valve, and means cooperating with said rod for substantially counteracting the effects of the variations in force exerted by the spring means and the bellows upon expansion and contraction thereof.

14. In a refrigerating system having a condenser, an evaporator and an expansion valve for controlling the flow of refrigerant from the condenser to the evaporator, the combination of, a pair of opposed extensible chambers, one end of each of said chambers being rigidly connected together and said ends having rigid imperforate wall portions forming pressure areas, means operatively connecting the expansion valve with the connection between said chambers for operation thereby, means subjecting one chamber to the low pressure side of the refrigerating system, means subjecting the other chamber to a pressure which corresponds to the temperature of the refrigerant at the evaporator outlet, a bellows within said last named chamber for decreasing the effective pressure area of the wall portion thereof and being of such size as to insure the maintenance of a substantially constant degree of superheat at the evaporator outlet for varying degrees of pressure and temperature at said outlet, and means for substantially counteracting the effects of the variations in force exerted by the extensible chambers upon expansion and contraction thereof.

15. In a refrigerating system having a condenser, an evaporator and an expansion valve for controlling the flow of refrigerant from the condenser to the evaporator, the combination of, means including an expansible chamber for positioning the expansion valve, means for supplying a restricted amount of refrigerant from the high pressure side of the refrigerating system to the expansible chamber, means for withdrawing refrigerant from the expansible chamber, means responsive to the condition of the refrigerant at the outlet of the evaporator for regulating the rate of withdrawal of refrigerant from the expansible chamber and means forming a second expansible chamber responsive to pressure at the outlet of the evaporator for positioning the expansion valve.

16. In a refrigerating system having a condenser, an evaporator and an expansion valve for controlling the flow of refrigerant from the condenser to the evaporator, operating means for positioning the expansion valve in a manner to maintain a substantially constant degree of superheat at the outlet of the evaporator, said operating means including an expansible chamber for positioning the expansion valve, means for supplying a restricted amount of refrigerant from the high pressure side of the refrigerating system to the expansible chamber, means for withdrawing refrigerant from the expansible chamber and means responsive to the temperature of the re-

frigerant at the outlet of the evaporator for regulating the rate of withdrawal of refrigerant from the expansible chamber.

17. In a refrigerating system having an evaporator, in combination, control means comprising an expansion valve, said valve including means forming a pressure chamber, restricted means for admitting high side refrigerant into said chamber, said chamber being arranged in a relatively warm region so as to evaporate the refrigerant therein, means for communicating refrigerant from said chamber to a point spaced therefrom, restricted means for causing refrigerant to escape from said communicating means,

said last restricted means being of a size to allow escape of gas at a slower rate than that at which refrigerant enters said chamber, means whereby said communicating means is subjected to the cooling effect of the relatively cool refrigerant at the outlet of the evaporator so as to cause refrigerant to condense in said communicating means and escape as a liquid from said last restricted means whereby a small amount of liquid tends to constantly stand in said communicating means so that the pressure in said chamber and communicating means corresponds to the condensation temperature of said liquid.
